ATTORNEYS.

UNITED STATES PATENT OFFICE.

EBER J. HAYMAN, OF PARKERSBURG, VIRGINIA.

ROOFING JOINT.

Application filed February 25, 1929. Serial No. 342,471.

The invention relates to the type of roof joint disclosed in Letters Patent of the United States granted to me Nov. 27, 1928, No. 1,693,274.

5 The invention consists in the features and combination and arrangement of parts hereinafter described and pointed out in the claims.

In the drawings:

10 Figure 1 is a cross sectional view of one form of the roof joint.

Fig. 2 is a side view of the parts shown in Fig. 1.

15 Fig. 3 is a view of the inner side of the joint, being substantially a view on section line 3—3 of Fig. 1, looking in the arrow direction.

20 Fig. 4 is a cross sectional view of another form of the invention in which a closing cap is used between the two sections of the roof.

Referring first to Figs. 1, 2 and 3, A and B are adjacent roof sections. At 1 the section A has an upstanding wall, which is 25 provided with a return bent portion 2, extending down from the upper edge of the upstanding wall at a divergent angle.

The other section B also has an upstanding wall and a return bent portion 4. This 30 covers or overlies the return bent wall of the section A. It has protuberances 5 struck out therefrom so as to project on the inner side. These protuberances do not break through the wall, but on the contrary 35 the wall is intact throughout and is continuous with the main wall portion of the flange or return bent portion. These protuberances form the locking means between the covering wall or flange 4 of the section 40 B and the underlying return bent portion of the section A. These flanges or return bent portions are resilient and when the covering wall 4 is pressed downwardly relative to the underlying return bent portion of 45 section A, the protuberances will snap under the edge of the underlying return bent portion and thus the covering wall will be locked to the underlying return bent portion or flange of section A.

50 Because the wall of the protuberance is continuous throughout and is continuous with the wall of the return bent portion or flange, the weather will be excluded from the interlocked parts and rusting will be 55 prevented.

It is desirable to prevent the elements

from reaching the contacting parts of the resilient lock particularly if there are raw edges exposed, as rust ensues from such exposure and damage follows not only to the 60 interlock but to adjacent surfaces, by reason of rust accumulations.

The protuberance is of special shape in that its lower point of juncture with the main body of the wall of the flange is along 65 a straight line as indicated at *a*. The configuration above this base line is that of an arch, and on the top of this arch the flange or return bent wall rests at the point *a*, the contact here being what might be termed 70 substantially a line contact, because the arched formation slopes away from this point of contact at either side. Viewed in section, as in Fig. 1, the projection presents a substantially abrupt shoulder at the point 75 *a*, with a slightly curved inner end at *b*, and a downwardly and outwardly inclined wall at *c* merging into the body of the flange.

By reason of this formation, the parts, 80 after being interlocked, readily can be slid relative to each other by a movement in the direction of the longitudinal edges of the joint, or the parts can be removed one from the other by a sliding movement in said 85 longitudinal direction. The disassembly can thus take place without damaging the flanges or the interlocking parts so that the joint can be made up again by using these same sections. The arched formation of the 90 projection contributes to this sliding action of one section relative to the other, because there is substantially but a line contact, and while from the standpoint of forming a lock this contact is amply sufficient, it reduces the frictional grip between the parts 95 to a minimum so that one will readily slide in relation to the other.

As above mentioned the return bent portions of the joint 2, 4 of Fig. 1 or 2^a, 100 4^a of Fig. 4 are resilient, there being sufficient spring in the galvanized sheet for these return bent portions to spring out of position and back again into their original positions when the joint is being assembled.

105 In making up the parts of the joint the sheets of metal are resquared so that they will have parallel sides while the sheets are in the black, that is, before they are galvanized. When galvanized the raw edges 110 will be coated along with the rest of the sheet.

In the form of the invention shown in Fig. 4 which is the preferred form, a cleat C' is used having its upper portion split and turned in opposite directions as at C¹, 5 C² to hold the sheet metal sections A¹ and B¹ to the roof. The cap D which provides the covering wall is placed in position by simply pressing it down over the upstanding and return bent portions of the sections 10 A¹, B¹.

In Fig. 1 the cleat C engages the upstanding portion of section A and fastens said section to the roof.

It will be seen from the above that the 15 two embodiments of the invention shown in Figs. 1 and 4 have features in common in that a spring lock exists between a return bent portion of a section and an overlying or covering wall, said lock consisting of a 20 preformed protuberance upset from and intact and continuous throughout with the said covering wall and presenting a shoulder to snap under the edge of the return bent portion and without regard to whether the 25 covering wall is in the form of a return bent portion of one of the sections or is a part of a separate cap member.

I claim:

1. A roofing joint comprising a section having an upstanding wall with a return bent portion depending from its upper edge and a covering wall having within its margin a preformed protuberance upset inwardly from its body, the wall of which is intact throughout and continuous with the main body wall and presents a shoulder to snap under and into interlocking engagement with the lower edge of the return bent portion when said covering wall is pressed downwardly relative to said return bent portion, substantially as described. 30 35

2. A roofing joint according to claim 1 in which the protuberance has an arch shaped wall contacting with the lower edge of the return bent portion substantially with a line 40 contact. 45

3. A roofing joint according to claim 1 in which the protuberance is of arched formation, presenting a substantially right angular shoulder to contact with the return bent portion, the inner end of said protuberance being rounded, substantially as described. 50

In testimony whereof, I affix my signature.
EBER J. HAYMAN.
